KITCHEN UTILITY MOP

Michael Polovitch, Elizabeth, N.J.

Application November 18, 1958, Serial No. 53,422

Term of patent 14 years

(Cl. D9—2)

I claim:

The ornamental design for a kitchen utility mop, as shown.
